Hilly.

UNITED STATES PATENT OFFICE.

ERNEST C. SMITH, OF CHICAGO, ILLINOIS, ASSIGNOR TO INTERNATIONAL HARVESTER COMPANY, A CORPORATION OF NEW JERSEY.

RATCHET DRIVE FOR CONVEYERS.

1,413,498.

Specification of Letters Patent. Patented Apr. 18, 1922.

Application filed March 26, 1920. Serial No. 369,075.

To all whom it may concern:

Be it known that I, ERNEST C. SMITH, a citizen of the United States, residing at Chicago, in the county of Cook and State of Illinois, have invented certain new and useful Improvements in Ratchet Drives for Conveyers, of which the following is a full, clear, and exact specification.

My invention relates to mechanical movements, and more particularly to one wherein reciprocating movement is translated into slow rotary movement through a pawl and ratchet device at variable degrees of speed.

One object of my invention is to provide a device of this type particularly adapted for use in connection with the conveyer or apron drive of a manure spreader, and which will meet all requirements of a drive in this location.

Another object is to simplify the construction of such drives and reduce the number of parts employed to a minimum, while providing means for varying the speed of transmission or rendering the transmission idle and assuring positive transmission of movement at all speeds.

With these and other objects in view, I employ a rocking lever or member having one arm connected to a pawl and ratchet device of novel construction fixed to the conveyer shaft, and its other arm connected to a reciprocating drive element actuated by an eccentric on the axle. The connection between the lever arm and drive element being also novel.

My invention, accordingly, consists of the organization, details of construction, parts, or their equivalents, hereinafter described, and more particularly defined in the claims.

Referring to the drawing—

Figure 1 is a side elevation of a spreader with my transmission mechanism applied thereto; and,

Fig. 2 is an enlarged plan view of the transmission mechanism.

My invention is illustrated in connection with a manure spreader comprising the usual wheel supported body A, at the rear of which there is mounted the beater B, secondary beater C, and scatterer D, all driven from the rear axle by mechanism on the other side

of the spreader body and not shown. Parts of the draft and steering gear are shown at E.

At the side of the spreader body near the rear there is secured an upright angle iron member 5 with one web extending outwardly. To this web there is secured a forwardly extending bracket 6, and on this bracket there is mounted a horizontally extending rocking member or lever 7. This member has its forward end vertically grooved or forked as indicated 8 (Fig. 2). This groove or fork cooperates with a strap 9 secured to the body of the spreader, and formed with a portion spaced therefrom which is engaged by said fork and acts as a guide for the member.

The member 7 has its forward arm formed with an arcuate slot 10, which extends from near the forked end of the arm rearwardly to a point in proximity to the pivot 11. At the point nearest the pivot the slot 10 widens and forms a triangular enlarged portion 12, which is of a width at its base equal to or slightly greater than the throw of the eccentric, hereinafter described.

The slot 10 receives the outwardly bent end 13 of a link 14, which passes under strap 9 and extends forwardly, and is connected to an adjusting lever 15 pivoted to the forward end of the spreader. Fixed to the axle 16 is an eccentric 17 which carries the eccentric ring 18, and to said ring is attached an arm or pitman 19 extending upwardly and pivotally connected to the bent end 13 of the link 14 at the outer side of the slot 10.

The drive shaft 20 for the apron or conveyer 20', is located below the end of the rearwardly extending arm of the rocking member 7, and has a ratchet wheel 21 fixed thereto. At opposite sides of the ratchet wheel arms 22 are pivotally mounted on the shaft 20, and extend forwardly and rearwardly respectively to a point beyond the periphery of the ratchet wheel, where they are bent or hooked and returned for some distance on the opposite side of said wheel.

At the rear end of the rocking member 7 there is pivotally connected a pair of links 23, the rear one of which is pivoted behind and below the forward link. These links

diverge downwardly, and their ends are bent inwardly at 24 and pass through the hooked ends of the arms 22 beyond the rim of wheel

21. On each of the bent ends 24 of the links 5 and within the hooked ends of arms 22 there is mounted a pawl 25, the rear one extending downwardly and the forward one upwardly, and each held in contact with the ratchet wheel by a spring 26.

10 It will be evident from the construction above described that rocking of the member 7 on its pivot will cause alternate engagement of the pawls 25 with the ratchet wheel, and cause a slow and almost continuous rotary movement of the shaft 20 to move the upper run of apron 20' in a rearward direction. The rocking of the member 7, as will be evident, is effected through reciprocation of the pitman 19, and the extent of 15 the rocking movement is determined by the position of the actuating element in the slot 10, the slowest movement being transmitted when it is at the extreme outer end of this slot.

25 When it is desired to render the transmission idle, the lever is drawn back to the position shown in Fig. 1, which places the actuating element in the widened part 12 of the slot, where it reciprocates idly. The 30 dotted line positions shown in Fig. 1 illustrate one active position of the mechanism.

It will be seen from the above description that I have provided a simple and effective device for the purposes described, and while 35 I have described a specific embodiment of my invention, any modification thereof within the scope of the appendant claims may be made.

What I claim as my invention is:

40 1. A drive mechanism comprising a rocking member having an arm, means for rocking the member including a reciprocating drive element shiftably connected with the arm, means for shifting the drive element 45 along the arm, and means for causing the rocking member to become inoperative when the drive element is shifted to a certain position on said arm.

2. A drive mechanism comprising a rocking member pivoted between its ends, means for rocking the member including a reciprocating drive element shiftably connected to one arm of said member, means for shifting the drive element along said arm, a driven 55 element operatively connected to the other arm of the member, and means for causing the drive element to operate idly when it is moved to one extreme of adjustment.

3. A drive mechanism comprising a rocking member pivoted between its ends and formed with a longitudinally extending slot in one arm, means for operating the rocking member including a pitman having one end shiftably received in said slot, means for 60 shifting the pitman along said slot, and

means for causing said rocking member to become inoperative when the pitman is moved to one end of the slot.

4. A drive mechanism for spreader aprons comprising a rocking member supported between its ends and having one of its arms formed with a slot enlarged at one end, a reciprocating drive element received in the slot, a driven element operatively connected to the other arm of the member, and means for shifting the drive element to and from the enlarged portion of the slot. 70

5. In a drive mechanism, a pivotally supported member formed with a longitudinal slot enlarged at one end, a reciprocating drive element received in the slot, and means for changing the position of the drive element in the slot. 75

6. In a drive mechanism, a pivotally supported member formed with a longitudinal slot enlarged at the end toward the pivot, a reciprocating drive element received in the slot, and means for changing the position of the drive element in the slot. 80

7. In a drive mechanism, a lever pivotally supported between its ends and with one arm formed with a longitudinal slot enlarged at one end, a reciprocating drive element received in the slot, and means for changing the position of the drive element in the slot. 90

8. In a drive mechanism, a lever pivotally supported between its ends and with one arm formed with a longitudinal slot enlarged at the end toward the pivot, a reciprocating drive element received in the slot, and means for changing the position of the drive element in the slot. 100

9. In a drive mechanism, a lever pivotally supported between its ends and with one arm formed with a slot which has a triangular enlarged portion at one end, a reciprocating drive element received in the slot and having a throw substantially equal to the length of the base of said enlargement, and means for shifting the reciprocating element from position in said enlargement, where it operates idly, to position in the other portion of the slot, where it rocks the lever. 110

10. In a drive mechanism, a centrally pivoted lever having one arm formed with an arcuate slot terminating at the end toward the pivot in a triangular enlarged portion, a reciprocating drive element connected in the slot and having a throw substantially equal to the length of the base of said enlargement, and means for shifting the reciprocating element from position in said enlargement, where it operates idly, to various positions in the arcuate part of the slot, 120 where it rocks the lever.

11. In a drive mechanism, a rocking arm having its free end forked, a fixed guide bar engaged by said fork, and means for rocking the arm comprising a reciprocating ele- 130

ment shiftable along the rocking arm to vary its throw.

12. A ratchet drive mechanism comprising a shaft, a ratchet wheel fixed thereto, an arm pivoted on the shaft at each side of the ratchet and hooked across its periphery, a driving member adapted to reciprocate toward and from said ratchet, a pair of links

pivoted to the member at different points and having their ends connected across the 10 hooked portion of said arms respectively, and a pawl on each cross portion of said links within the arm hooks and oppositely engaged with the ratchet.

In testimony whereof I affix my signature. 15
ERNEST C. SMITH.
